ATTORNEY.

UNITED STATES PATENT OFFICE.

WILLIAM T. CHAMBERLAIN, OF NORWICH, CONNECTICUT, ASSIGNOR OF
TWO-THIRDS TO BENJAMIN M. PRINCE, OF SAME PLACE, AND WILLIAM
CROSSLEY, OF RANDOLPH, MASSACHUSETTS.

PNEUMATIC PROJECTILE.

SPECIFICATION forming part of Letters Patent No. 312,971, dated February 24, 1885.

Application filed June 18, 1884. (No model.)

To all whom it may concern:

Be it known that I, WILLIAM T. CHAMBERLAIN, a citizen of the United States, residing at Norwich, in the county of New London, State of Connecticut, have invented a new and useful Improvement in Projectiles, which improvement is fully set forth in the following specification and accompanying drawings, in which—

10 Figure 1 is a longitudinal section of a projectile embodying my invention. Fig. 2 is an end view thereof. Fig. 3 is an end view of a detached part of the gun or fire-arm with which the projectile is employed.

15 Similar letters of reference indicate corresponding parts in the several figures.

My invention consists of a projectile having a chamber for compressed air and an inlet and outlet for the same, said outlet being 20 closed by a plug, which, when removed, permits the escape of the air, so that the projectile is impelled, as will be hereinafter fully set forth.

Referring to the drawings, A represents a 25 projectile, which is formed with a suitable point, a, a chamber, b, for compressed air, and a tubular base, c.

In the wall of the chamber b is an air opening or inlet, d, which is covered by an inwardly-opening valve, d', the latter being 30 properly secured within the chamber, it being noticed that the tubular base c constitutes the outlet for the air of the chamber b.

B represents a screw-plug, which is fitted 35 to the base c, the wall whereof is threaded for the engagement of said plug.

Within the gun or other fire-arm is fitted, at the base of the bore thereof, a rotary head, C, the stem C' whereof passes through the 40 breech-wall, and is provided with a suitable handle, C''.

In the outer face of the plug B is an opening, e, to receive the angular or squared portion D at the forward end of the stem C, or 45 a lug formed on or secured to the front face of the head C.

In the outer face of the base c is an opening, f, to receive a pin, E, on the front face of the guide C'' of the head C, it being noticed

that said guide abuts against the wall at the 50 base of the bore of the fire-arm, and the stem C is swiveled in said guide.

Air is forced into the chamber b in any desirable manner, the valve d' opening to permit the same, it being noticed that the base c 55 is closed by the plug B, and when the projectile is charged with the compressed air the valve d' closes and the projectile is introduced into the gun or fire-arm, so that the lug D and pin E enter the openings e f, respectively. 60

When the fire-arm is to be discharged, the handle C'' is rotated, whereby the plug B is also rotated. The pin E prevents rotation of the projectile, and as the plug B is unscrewed from the base c, and it bears against the guide 65 C'', the projectile is slightly advanced. When the plug is fully unscrewed from the base c, the opening of the latter is uncovered and the compressed air is liberated, the reaction whereof in the fire-arm at the base of the bore 70 forcibly impels the projectile from the arm, the result being accomplished without the smell, smoke, heat, and fouling tendency of powder-charged projectiles, another advantage of the invention being that by its use the 75 danger incident to the transportation and handling of explosives is avoided.

It is evident that the head C may have play in the fire-arm, so as to move rearward as it rotates and unscrews the plug B to avoid moving the projectile.

Having thus described my invention, what I claim as new, and desire to secure by Letters Patent, is—

1. A projectile having a chamber for compressed air, an inlet for the same, a valve closing said inlet, an air-outlet, and a rotary plug removably connected with said outlet, whereby when the plug is operated the air-outlet is opened or uncovered, substantially as 90 and for the purpose set forth.

2. An air-charged projectile, in combination with a fire-arm having a rotary head which is fitted to the base of the bore thereof and provided with a suitable handle, said head being connectible with a rotary plug at the discharge end of the projectile, so as to operate the same and thus open the air-outlet of the 95

projectile, substantially as and for the purpose set forth.

3. An air-charged projectile having a tubular base, and a removable plug fitted to said base, said base and plug having each an opening on its outer face, in combination with a rotary head fitted to a fire-arm provided with a lug, and a pin to engage with the openings,

respectively, of the base and plug of the projectile, for preventing rotation of the projectile and removing the plug thereof, substantially as and for the purpose set forth.

WILLIAM T. CHAMBERLAIN.
